HEMMING ATTACHMENT FOR SEWING MACHINES

John P. Enos, Union, N. J., assignor to The Singer Manufacturing Company, Elizabeth, N. J., a corporation of New Jersey

Application December 2, 1947, Serial No. 789,208

2 Claims. (Cl. 112—143)

1

This invention relates to hemming attachments for sewing machines and more particularly to a narrow hem forming attachment of the type having a pair of complementary spiral scroll-members for hem-folding the margin of a necktie or handkerchief and directing the hem-folded margin to the needle of a sewing machine.

The present prevalent use of synthetic fabrics such as rayon and the like in the manufacture of neckties presents a difficult problem in the production of narrow uniform hems along the edge of the material. The synthetic fabrics readily ravel along the marginal edge and particularly so when any strain is applied to the fabric against the grain. However, it has been found that if the marginal edge of the fabric is properly handled and controlled the resultant hem is very compact and uniform in width.

To obtain a satisfactory hem on the various kinds and weaves of synthetic fabrics it is desirable that the hemming attachment be constructed so that the capacity of the fabric passageway between the scroll-members can be varied in accordance with the material being used.

It is, therefore, the primary object of the present invention to provide a scroll-hemmer in which one of the complementary scroll-members is mounted to turn on an axis normal to the longitudinal axis of the hemmer for limited adjustment relative to the other scroll-member, for the purpose of permitting an exact setting of the capacity of the fabric passageway between the scroll-members to avoid excessively straining the fabric and causing raveling thereof.

The foregoing and other objects and advantages in view, together with means whereby the same may be carried into effect, will best be understood from the following description of a preferred embodiment of the invention illustrated in the accompanying drawings, in which:

Fig. 1 is a side elevation of a scroll-hemmer embodying the present invention.

Fig. 2 is a top plan view of the scroll-hemmer.

Fig. 3 is a transverse sectional view taken substantially along the line 3—3, Fig. 2.

Fig. 4 is a top plan view of the base-plate of the attachment.

Fig. 5 is a top plan view of the primary scroll-member having an adjusting screw threaded through the upturned limb thereof.

Fig. 6 is a top plan view of the secondary scroll-member.

Referring more in detail to the drawings, the hemming attachment comprises a base plate 10 fitted at one end with the usual depending fasten-

ing screw 11 which is adapted to project through a suitable hole in the bed-plate of a conventional sewing machine and have threaded upon it a clamping nut (not shown) for holding the hemmer in operative position. At its other end, the base-plate 10 is formed with a downturned lip 12 which is adapted to extend into a locating hole in the usual throat-plate to assist in maintaining the hemmer in proper alignment with the sewing machine stitching devices.

Adjustably mounted on the base-plate 10 is the shank 13 of a primary scroll-member 14; the shank 13 being formed with an elongated hole 15 through which extends a clamping screw 16 threaded into a reinforced portion 17 of the base-plate 10. The elongated hole 15 and the clamping screw 16 provide means for permitting adjustment of the hemmer toward and from the stitching devices of the sewing machine. At its rear end the shank 13 is preferably bent downwardly, as at 18, to substantially rest, when in use, upon the usual cloth-plate of the sewing machine to provide an inclined guiding surface facilitating the introduction of the work into the mouth of the hemmer. Substantially midway of its length, the primary scroll-member 14 is formed with a lateral extension 19 providing a fulcrum support for the overlying thickened shank 20 of a secondary scroll-member 21 spiralled in conformity with the primary scroll-member 14 to define a fabric passageway 22 (Fig. 1) extending from the receiving end or mouth 23 to the delivery end 24 of the attachment. Extending through substantially vertically aligned holes 25 and 26 in the lateral extension 19 and the thickened shank 20 is a pivot-stud 27 having an eccentrically formed body 28 embraced by the thickened shank 20 of the secondary scroll-member 21. Turning of the pivot-stud 27 effects a bodily shift of the secondary scroll-member 21 relative to the primary scroll-member 14, resulting in a change in the capacity or size of the fabric passageway 22 defined by the two scroll-members. It will be appreciated that by opening or closing the two scroll-members when turning the pivot-stud 27, the fabric as it traverses the hemmer is pinched or strained more or less, depending on the relative spacing of the two scroll-members 14 and 21. If the fabric passageway is too small the fabric is excessively pinched or strained and the raw edge of the fabric which is being hemmed becomes frayed to the point where successful hemming thereof is impossible. On the other hand, if the fabric passageway is too large, the marginal edge 55 of the fabric is not properly controlled and this

results in an incomplete hem-fold. Obviously, the attachment to be satisfactory must be arranged so that its capacity can be controlled to an accurate degree.

To assist in obtaining the exact relative adjustment of the two scroll-members 14 and 21 and to provide an abutment for maintaining the adjusted position of the scroll-members, there is provided an adjusting screw 29 which is threaded into an upstanding limb 30 of a right angle bracket 31 soldered to the under face of the lateral extension 19, the inner end of the adjusting screw 29 bearing against the thickened shank 20 of the secondary scroll-member 21. The thickened shank 20 is held in contact with the inner end of the adjusting screw 29 by a coil-spring 32 acting between the shank 20 and the upstanding limb 30 of the right angle bracket 31. The adjusting screw 29 is frictionally held against turning by a compression spring 33 which is coiled about the adjusting screw. It will be observed in Fig. 2 that the adjusting screw 29 and the spring 32 engage the thickened shank 20 of the secondary scroll-member 21 on opposite sides of the pivot-stud 27, and that the spring acts to yieldingly maintain the secondary scroll-member in adjusted position. Obviously by turning the adjusting screw 29 the secondary scroll-member is caused to pivot about the pivot-stud 27 and by this means a micrometer adjustment of the capacity of the fabric passageway 22 is obtained. The hemming attachment disclosed is not subject to choking when cross-seams or the like in the material pass through the attachment for the reason that the spring 32 permits a limited yielding movement of the secondary scroll-member relative to the primary scroll-member, which yielding movement augments the inherent flexing of the two scroll-members.

Having thus set forth the nature of the invention, what I claim herein is:

1. A hemming attachment for sewing machines comprising, a longitudinally spiraled primary scroll-member, a longitudinally spiraled secondary scroll-member complementary to said primary scroll-member in defining a fabric passageway therebetween, and a stud supporting one of said scroll-members on the other of said scroll-members, said stud having an eccentric body-portion embraced by one of said scroll-members so that turning of said stud will effect a shift of one of said scroll-members relative to the other of said scroll-members for adjustment of the capacity of the fabric passageway between said scroll-members.

2. A hemming attachment for sewing machines comprising, a longitudinal spiraled primary scroll-member having a lateral extension formed with an upturned lip, a longitudinal spiraled secondary scroll-member cooperating with said primary scroll-member to define a fabric passageway, a shank supporting said secondary scroll-member and disposed upon said lateral extension, a stud extending through said shank and secured to said lateral extension, an adjusting screw threaded into said lip and engaging said shank at one side of said stud, and a spring at the other side of said stud acting between said lip and said shank.
